CUE TIP

Filed Jan. 25, 1922

UNITED STATES PATENT OFFICE.

JOHN LUKAS DORSCHEL, OF KITCHENER, ONTARIO, CANADA.

CUE TIP.

Application filed January 25, 1922. Serial No. 531,695.

To all whom it may concern:

Be it known that I, JOHN L. DORSCHEL, a citizen of the United States, and resident of Kitchener, in the Province of Ontario and Dominion of Canada, have invented certain new and useful Improvements in Cue-Tips, of which the following is a specification.

This invention relates to tips especially adapted for application to cues.

An important object of this invention is to provide a cue tip having novel means whereby the same may be securely connected to a cue without employing glue and which when applied is securely held in position until worn out.

A further object is to provide a cue tip which may be applied in a few seconds and which is of highly simplified construction and cheap to manufacture.

Other objects and advantages of the invention will be apparent during the course of the following description.

In the accompanying drawing:

25 Figure 1 is a fragmentary perspective of a cue equipped with the improved tip.

Figure 2 is a sectional view through the tip applied.

30 Figure 3 is a transverse sectional view taken on line 3—3 of Figure 2.

Figure 4 is a transverse sectional view taken on line 4—4 of Figure 2.

35 Figure 5 is a perspective of a spring clip embodied in the invention.

40 In the drawing the numeral 5 designates a cue the forward end of which is rabbeted as indicated at 6 to define an extension adapted to be received within a shallow socket in the rear portion of a head 7. The head 7 may be of hard rubber or other suitable material and is provided with a centrally arranged opening 8 through which a screw or other fastening device 9 extends for detachably securing the head to the forward end of the cue. The head 10 of the screw is received in a counterbored portion of the head 7 and is flush with the head 7.

45 The tip consists of a pair of sections 12 and 14 of leather or other suitable material, the outer section 12 being somewhat rounded as illustrated in Figure 2 and connected to the section 14 by an adhesive 16. The connection between the sections 14 and 12 is more or less permanent and the heads 18 of attaching pins 20 are confined between the sections 12 and 14 whereby the pins 20 are

permanently and securely connected to the tip.

As illustrated in Figure 2 the attaching pins 20 of which there may be any desired number are extended rearwardly into openings 21 in the head 7 whereby to connect the tip to the head. When the attaching pins 20 are extended into the head 7 they engage spring clips generally designated by the numeral 25 and clearly illustrated in Figure 5. Each spring clip is formed from a single length of metal bent between its longitudinal edges to provide a pair of gripping members 26 adapted to contact with the opposite sides of the attaching pins 20 whereby to securely hold the same in position. When the tapered forward ends of the pins 20 are forced between the transversely curved sides 26 of the clips the sides are, of course, spread somewhat and flatly contact with the pins so as to securely hold the pins in position. The sides 26 of the spring clips 25 are curved inwardly as indicated at 28 so as to define more or less yieldable tubes into which the pins are extended.

With reference to Figure 2 it will be seen that the forward ends of the openings 21 within which the spring clips are arranged are reduced to form shoulders 30 which limit the forward movement of the spring clips. This permits the pins 20 to be withdrawn without the possibility of drawing the clips out through the forward end of the head. Also by reducing the forward ends of the openings 21 the openings guide the pins 20 into the proper portions of the spring clips. In other words, the forward portions of the openings 21 are of a size to 90 snugly receive the attaching pins 20.

While the pins 20 hold the tip against lateral movement or displacement a tongue and groove connection may be provided between the tip and the head and in that case the forward portion of the head 7 is provided with annular grooves 36 which receive tongues 37 formed on the inner side of the section 14.

In use when the tip is connected to the head 7 by means of the pins it is positively held against displacement and remains in place until completely worn out. The tip may be readily removed by simply withdrawing the pins 20 and a new tip may be 110 readily attached.

The head 7 and spring clips 25 are in-

destructible and the tip will remain in place until worn out, without the possibility of injuring the cue or ball.

Having thus described the invention what I claim is:

1. A cue tip consisting of a head having means whereby the same may be secured to the forward end of a cue, said head being provided with a plurality of longitudinally extending openings, spring clips received in said openings, a tip applied to the forward end of said head, and fastening pins extended into said clips and securely engaged thereby whereby to hold said tip in engagement with said head.
- 10 2. A cue tip consisting of a head having means whereby the same may be secured to the forward end of a cue, said head being provided with a plurality of longitudinally extending openings, spring clips received in said openings, a tip applied to the forward end of said head, fastening pins extended into said clips and securely engaged thereby whereby to hold said tip in engagement with said head, the forward portions of said openings being reduced to snugly receive said pins and to define shoulders limiting the forward movement of said clips.
- 20 3. A cue tip consisting of a head having means whereby the same may be secured to the forward end of a cue, said head being provided with a plurality of longitudinally extending openings, spring clips received in said openings, a tip applied to the forward end of said head, and fastening pins extended into said clips and securely engaged thereby whereby to hold said tip in engagement with said head, said clips being formed from spring metal bent to provide yieldable sides engaging the pin, said sides being curved transversely.
- 30 4. A cue tip consisting of a head having

means whereby the same may be secured to the forward end of a cue, said head being provided with a plurality of longitudinally extending openings, spring clips received in said openings, a tip applied to the forward end of said head, and fastening pins extended into said clips and securely engaged thereby whereby to hold said tip in engagement with said head, there being a tongue and groove connection between said tip and said head.

5. A cue tip consisting of a body having its forward portion rabbeted, a head having a shallow socket receiving the forward portion of said cue, said head being provided with longitudinally extending openings, spring clips extending through said openings and contacting with the forward ends of said cue, the forward portion of said openings being reduced to provide shoulders engaging the forward ends of said spring clips to limit the forward movement of the same, a tip applied to the forward end of said head, fastening pins carried by said tip and extending through the reduced portion of said opening and into said spring clips, and an attaching screw extended through said head and into said body, said spring clips being formed from single lengths of metal bent between their longitudinal edges to provide yieldable sides, said sides being adapted to contact with said pins to hold the pins securely in position.

6. In a cue, the combination of a head, spring fastening clips carried thereby and having longitudinal openings, a tip arranged at the forward portion of the head, and fastening pins carried by said tip and securely and detachably received in the longitudinal openings in said spring clips.

JOHN LUKAS DORSCHEL.
